UNITED STATES PATENT OFFICE.

JOHN H. STONEMETZ, OF BROOKLYN, NEW YORK, ASSIGNOR, BY MESNE ASSIGNMENTS, TO THE CAMPBELL PRINTING PRESS & MANUFACTURING COMPANY, OF NEW YORK, N. Y., A CORPORATION OF NEW YORK.

PRINTING-PRESS.

SPECIFICATION forming part of Letters Patent No. 693,183, dated February 11, 1902.

Application filed September 22, 1892. Renewed July 1, 1901. Serial No. 67,010. (No model.)

To all whom it may concern:

Be it known that I, JOHN H. STONEMETZ, a citizen of the United States, residing at Brooklyn, in the county of Kings and State of New York, have invented a new and useful Improvement in Printing-Presses, of which the following is a specification.

The aim of this invention is to improve the details of the printing-machine shown in Letters Patent granted to me January 3, 1888, No. 376,053; and to this end the invention consists of the device described and claimed in this specification and illustrated in the accompanying drawings, in which—

15 Figure 1 is a side elevation of enough of a machine to illustrate my improvements. Fig. 2 is a sectional diagrammatic elevation. Figs. 3, 4, and 5 are details of the inking mechanism of the carriage. Figs. 6, 7, and 8 are details of the pawl mechanism used in the intermittently-operating delivery device, and Fig. 9 is a detail of the cam actuating the brake used in the feeding mechanism.

25 The driving mechanism for moving the impression-cylinders and the way the impression-cylinder carriage is mounted to slide on the frame have been omitted, as the same are not necessary to a full understanding of this case.

30 Referring to the drawings and in detail, A and B represent the two reciprocating impression-cylinders, and C and D the form-beds, with which said cylinders are adapted to coöperate. The cylinders A and B may be mounted in any suitable carriage or framing, as E.

The roll F, from which the web is led, is mounted above the form-beds, as shown. From roll F the web is led around the rollers 40 4, 5, and 6, which are continuously driven, to slowly unwind the web from the roll, then around the looping-roller 7, which is mounted in arms 8, which are carried by arms 9, which have weights 10, which arms 9 are journaled on the shaft 11, and then the web passes around the roller 12, which is loosely journaled in the main framing, as shown, and with which roller 12 a brake 13 coöperates. From the roller 12 the web passes to the roller

14, mounted at the end of the press, which 50 roller 14 is continuously driven, for a purpose hereinafter described. From the roller 14 the web passes around guide 15, carried by the carriage, around the impression-cylinder A, around guide 16, also carried by the carriage, 55 across the machine to the roller 17, which is mounted at the other end of the press and is also continuously driven back to the guide or bar 18, carried by the carriage, around the impression-cylinder B, around guide 19, between the rollers 20 and 21, which may be also continuously driven, to and between the intermittently-operating delivery-rollers 22 and 23. By this passage of the web it will be seen that the same will be printed as in my 65 Letters Patent before referred to. From the rollers 22 and 23 the end of the web is intermittently delivered over guide 24 between the knives 25 and 26, the upper knife 26 of which may be reciprocated by a mechanism substantially as shown in Letters Patent to Kidder, No. 224,440, dated February 10, 1880, and from the knife the sheet is passed on to the continuously-running tapes 29, which 70 pass over the pulleys 27 and 28, whereby the sheet is brought up against a suitable stop and is then tucked between the folding-rollers 30 by the blade 31, and then is carried from the roller 30 by suitable tapes (not 75 shown) over the rollers 32 and 33, and is 80 then tucked by the knife 34 between said folding-rollers, and is then delivered by fly 35 down on the slowly-running delivery-tapes 50, which pass around the rollers 36 and 37.

It is not thought necessary to show the details of the knife-operating mechanism or of the folder more at length, the only novel point in regard to the folder being its peculiar relation with regard to the beds—that is, the folder is placed substantially under one of the 90 beds, whereby space is economized and the machine made very compact.

Mounted at each end of the frame is an ink-fountain G, and from these fountains ink is taken by the ductor-rollers 38, which are suitably operated from the shafts 39 and deposited upon the drum-cylinders 40, and from the drum-cylinders 40 the ink is carried by the

composition-rollers 41 and 42 to the drum-cylinders 43 and 44, which are arranged, as shown, at the outer end of each bed.

The usual gearing, consisting of racks R 5 and the gears S, mounted on the side of the impression-cylinders, is used to keep the cylinders in register with the beds.

Arranged on each side of each impression-cylinder is a distributing-roller 470, which is 10 positively rotated from the gear S by means of intermediates 45 and 46, as shown, and co-acting with each of these distributing-rollers is a plurality of form-rollers, as 48 and 49. Thus there are two form-rollers and a 15 distributing-roller on each side of each impression-cylinder.

The gearing for driving this various mechanism may be arranged as follows: A driving-shaft 51 is arranged in the main frame, and 20 on this shaft is arranged a pinion 52, which meshes with and drives gear 53, and attached to the gear 53 is a bevel-gear 54, which meshes with and drives bevel-gear 55, arranged on the parallel shaft 56, as shown. Also arranged to turn with gears 53 and 54 is a cam 57, engaging which is a yoke 58, which has suitable rollers 59 and 60 bearing on the sides of the cam, and this yoke connects to a suitable bell-crank lever 61, which has a suitable 25 toothed segment on the end thereof, which meshes with and thereby oscillates pinion 62, which pinion 62, by means of a ratchet mechanism hereinafter described, intermittently imparts motion in one direction to gear 63, which 30 gear 63 drives the pinion 64, and thereby the gears 65 and 66, whereby the delivery-rollers 22 and 23 are intermittently turned to deliver the web from the press. Also arranged on the shaft 56 is a bevel-gear 67, which meshes 35 with and drives gear 68, fast on shaft 69, which shaft 69 carries a bevel-gear 100, and by means of this bevel-gear 100 and another bevel-gear 101, arranged on the shaft of the roller 5, the rollers 4, 5, and 6 are continuously turned to 40 slowly unwind the web, the rollers 4, 5, and 6 being geared together, as shown. From the gear on the roller 4, by means of a suitable intermediate 102 and gears 103 and 104, the rollers 20 and 21 are positively and continuously turned. Also mounted on the shaft 45 56 is a cam 69, which has suitable depressions 690, and engaging this cam is a yoke 70, which carries a roller 71, and this yoke 70 connects to an arm 73 on the shaft of the 50 brake 13, and a suitable spring 72 is arranged, as shown, so as normally to throw the brake off, but the cam will tend to keep the brake tightly against the roller 12. Arranged near the ends of the shaft 56 are bevel-gears 74, 55 which mesh with and drive pinions 75, mounted on shafts 750. Also arranged on each of these shafts 750 is a bevel-pinion 76, which meshes with and drives a bevel-pinion 77, and by means of gearing, as 78, 79, 800, 80, 60 and 81, the inking mechanism at each end of 65 the press is positively turned. From this gearing gears 87 are also turned, and on the

ends of the shafts of these gears 87 are arranged suitable eccentrics 88 and connections whereby the ductor-rollers 38 will be vibrated 70 at the proper time to take ink from the fountains G and deposit the same on the rollers 40. Near the top of each of the shafts 750 is arranged a bevel-gear 82, and by means of bevel-pinions 83, 84, and 85 these bevel-gears 75 82 continuously rotate and drive the roller 14 or 17, as the case may be. Arranged on the ends of the shaft 56 are slotted crank-arms 90, and by means of suitable connections 91 and ratchets 92 the rollers of the ink-fountains G are slowly turned in the usual manner.

Referring now to Sheet 3 for a specific description of the inking mechanism carried by the carriage, it will be seen that the inside form-rollers 49 are dropping-rollers and are 85 carried by suitable arms 111, which are pivoted or may be caught on the shaft 110 of the form-rollers 48, the form-rollers 49 being mounted on suitable shafts 112 for this purpose. The form-rollers 49 are kept in fixed 90 contact with the distributing-rollers 470 by means of springs 113. On the ends of the shafts 110 are arranged suitable fingers 120 or 122, as shown in Fig. 3, and fixed to each end of the main frame are suitable cam-arms 95 121 and 123, and the cam-arms 121 and 123 and their coacting fingers 120 and 122 are arranged in different planes, whereby the fingers 120 will never coact with the arm 123. By means of these cam-arms when the cylinders are at their extremes in either direction the inside form-rollers of the cylinder that is outstanding over an inking apparatus will be depressed to positively engage the distributing-cylinders 43 and 44, and as these 100 distributing-cylinders 43 and 44 are rotated the form-rollers 49 will be rapidly turned and a quantity of ink will be taken up by the same. Then when the cylinders start to move back over the bed the springs will pull 110 the form-rollers 48 against the distributing-rollers 470, and thus the ink will be taken up also by the form-rollers 48, which bear against the distributing-rollers 470, whereby 115 ink can be taken by each set of distributing-rollers on each side of one of the cylinders when the cylinders reverse, as shown. By this mechanism a very simple and efficient 120 inking apparatus is provided, which will give a great and nice distribution and with which the press can be rapidly run.

It is necessary in the operation before described to use a ratchet or equivalent mechanism, so that the oscillatory motion given 125 pinion 62 will transmit an intermittent motion in the same direction to the gear 63. To do this, the ratchet mechanism, such as is substantially shown in the patent to Kidder, before referred to, may be used, and the way I may arrange the same is as follows: A stud 130 130, having a suitable head 131, is fastened to the main frame by the nut 132. The pinion 62 has a suitable chambered-out sleeve 136, and the gear 63 has a similar chambered-

out sleeve 134; but, as shown, the inside diameter of the sleeve 134 is slightly less than that of the sleeve 136. Passing through the pinion 62 is a pin 133, and mounted on this pin is a suitable shoe or pawl 135, which is normally held against the rim 134 by means of spring 137, bearing against the lug 138, carried by the sleeve 136. Thus as the pinion 62 is turned in one direction the shoe or pawl 135 will cramp and will turn the gear 63; but when the pinion 62 is turned in the other direction the shoe or pawl will not tend to cramp, but will slide loosely in the sleeve 134, and thus will not affect gear 63.

15 The operation of my machine thus organized is apparent, and is as follows: The web is slowly unwound from the roll F, and as the same is unwound it is looped up by the roller 8. When the cylinders have finished their 20 printing stroke in either direction, the rollers 22 and 23 will be quickly revolved, the brake 13 at this instant being removed from the roller 12, whereby the slack paid out to the 25 looping-roller 7 will be pulled through the press, and the cylinders can then move back to print the next sheet; but during the printing operation the brake 13 will tightly bite the roller 12, and will thus prevent the drag on the web in the press from affecting 30 the action of the looping-roller. The web thus delivered forward by the intermittently-operated rollers 22 and 23 will be cut off into sheets by the knives 25 and 26, will be folded by the folding mechanism, and delivered by 35 the fly onto the slowly-running tapes 50.

By the mechanism previously described it will have been noted that the rollers 14 and 17 are continuously and rapidly revolved to draw the web forward; but when the web is 40 held by the brake 13 these rollers 14 and 17 will simply loosely pull on the web and will not affect its action. In some cases I do not intend to drive the rollers 20 and 21 continuously; but I prefer in most cases to do so, 45 because by slightly pulling the web forward any slack that may occur beyond the brake will be quickly taken up and will not affect the printing operation. By having these guide-rollers 14, 17, and 20 continuously revolving, when the brake 13 is released and the rollers 22 and 23 started the web will be 50 very quickly moved, as the same will not have to be strained its entire length before the same will be started, and this adds greatly to 55 the quick operation of the web. The rollers 20 and 21 do not tightly bear against each other, but the web runs easily between the same, so that they can turn without pulling the web forward sufficiently hard to break 60 the same.

It will be seen that when the cylinders are at their left-hand extreme the form-rollers near the impression-cylinder A will receive their supply of ink, and that when the impression-cylinders are in their right-hand extreme the form-rollers near the impression-cylinder B will receive their supply of

ink. Thus only two fountains are needed for the entire machine, and also it will be seen that the form-rollers are arranged on each side of each impression-cylinder. This operation will serve to evenly ink the forms, whereby both impressions will be the same. Thus, for example, take the case of the sheets printed by the impression-cylinder A. In the position shown the cylinder has just been moved to the left, the web has just been fed forward, and the impression-cylinder is now started on its movement to the right. On the previous movement to the left the right-hand form-rollers 48 and 49 will have inked the form, and now the right-hand form-rollers have just received a new supply of ink and will thus again ink the form as the impression-cylinder A prints on its right-hand movement. As the cylinder A moves to the right the ink that has just been taken up by the left-hand form-roller 49 will be spread on the form by the left-hand form-rollers 48 and 49, and when the impression-cylinder A moves again to the left the left-hand form-rollers 48 and 49 will pass back over the form on the bed C, and thus the form-rollers on each side of the impression-cylinder will run twice over the form before the impression is taken in either direction, and as two form-rollers are used on each side of the impression-cylinder a very nice distribution is obtained.

A further description of the detailed parts is not thought necessary.

The details herein shown and claimed may be applied to other forms of presses than that illustrated, and especially some of them may be applied to a form of press with the beds arranged one over the other.

Having thus fully described my invention, what I claim, and desire to secure by Letters Patent, is—

1. The combination in a printing-press of a stationary form-bed, a traveling carriage carrying an impression-cylinder coacting with the form-bed, a form-inking roller mounted in the carriage at each side of the impression-cylinder, and a single ink-supplying mechanism comprising independent distributing devices arranged to supply ink to each of said form-rollers when the impression-cylinder is over the inking apparatus.

2. The combination in a printing-press of a form-bed, a traveling impression-cylinder cooperating therewith, a form-roller mounted on each side of the impression-cylinder, a single inking apparatus mounted at one end of the bed and containing two distributing cylinders arranged to supply ink to both said form-rollers when the impression-cylinder is off impression toward the inking apparatus.

3. The combination in a printing-press of a form-bed, a traveling impression-cylinder cooperating therewith, a form-roller mounted on each side of said impression-cylinder, two distributing-cylinders arranged at one end of said bed, and a single ink-fountain arranged to supply ink to both of said distributing-cyl-

inders, the whole so arranged that said form-rollers will take ink from said distributing-cylinders when the impression-cylinder is off the form-bed.

5. 4. The combination in a printing-press of a form-bed, a traveling impression-cylinder coöperating therewith, a dropping form-roller and a distributing-roller mounted at each side of the impression-cylinder, an ink-supplying apparatus arranged at one end of the bed, and means whereby said dropping-rollers will leave their distributing-rollers and obtain ink from said ink-supplying device when the impression-cylinder is off impression.

15. 5. The combination in a printing-press of a form-bed, a traveling impression-cylinder coöperating therewith, form-rollers and distributing-rollers mounted at each side of said impression-cylinder, an ink-supplying device for said form-rollers arranged at one end of said bed, and means whereby said form-rollers will leave their distributing-rollers, and take ink from the supplying apparatus when the impression-cylinder is off impression.

20. 6. The combination in a printing-press of a form-bed, a traveling impression-cylinder coacting therewith, two form-rollers and a distributing-roller arranged at each side of said impression-cylinder, an ink-supplying device for both of said sets of form-inking rollers arranged at one end of the bed, and means whereby one of the form-rollers of each set

will leave its distributing-roller and take a supply of ink from the supplying apparatus 35 when the impression-cylinder is off impression.

7. The combination in a printing-press of two form-beds, a traveling impression-cylinder coacting with each form-bed, a plurality 40 of form-inking rollers arranged at each side of each of said cylinders, an inking apparatus comprising two distributing-cylinders, and means for supplying ink to said distributing-cylinders arranged at one end of each of said 45 beds, and means whereby one of the form-rollers at each side of each impression-cylinder will take ink from the distributing-cylinders.

8. The combination in a printing-press of 50 two form-beds arranged in horizontal planes, a traveling carriage carrying an impression-cylinder coacting with each of said form-beds, a form-roller arranged at each side of each impression-cylinder, and an inking apparatus comprising two distributing-cylinders, and means for supplying ink to said distributing-cylinders arranged at the outer end of each of said beds.

In testimony whereof I have hereunto set 60 my hand in the presence of two subscribing witnesses.

JOHN H. STONEMETZ.
